DEVICE FOR HANDLING CARTONS AND THE
LIKE

Claude W. Davis, Los Angeles, Calif.

Application June 20, 1938, Serial No. 214,683
Renewed April 26, 1940

5 Claims. (Cl. 294—27)

My invention relates to lifting devices or tongs, and more particularly to devices for lifting, carrying and otherwise handling any article which presents a thin wall, which wall of itself, or through imposed load, reacts so that its effective center of gravity is offset or angular to the direction at which the force is applied. This applies to lifting of cartons, cans, tanks, boxes and other containers as well as to any article or material in sheet form, and the invention is applicable both to penetrable or deformable material as well as to more dense and rigid material.

While the invention is not limited thereto, it is an object to provide a lifting device particularly for lifting, carrying, and otherwise handling paper cartons containing wholesale quantities of ice cream. I am aware that devices are known for handling cartons of this type, either with or without the cover removed, but I consider prior devices objectionable and unsafe in that they depend either upon engaging a prominent flange or upon piercing the paper to such extent that the load is supported solely by the margins of the perforations made in the paper.

While the present invention takes advantage wherever possible of a flange, beading or the like to aid the device in its action, and while I do not go so far as to say that I can safely lift and transport a paper carton of appreciable weight by frictional grip alone, I have sought to provide for lifting cream-filled paper cartons by combining the advantages of prior devices and eliminating the disadvantages thereof.

A particular object of my invention is to provide for engaging, lifting and carrying a cream-filled paper-walled container without depending upon either a flange or perforations, but rather by combining slight penetration of the paper, slight engagement between the device and the beading or rim of the container, and friction, respectively to insure the ideal lifting and holding effect under all conditions without depending on one action alone.

One prior device, for example, causes the paper container to be pierced and to be suspended solely by the tearing strength of the paper, which, of course, varies with conditions and is not a dependable factor. An object of my invention is to provide for controlling the degree of penetration and for combining friction and partial penetration to effect a greater holding power, without depending so much on the tearing strength of the paper.

Another type of prior device depends on a hooked instrument for engaging either the bot-

tom surface or a protruding flange of a container. Modern ice-cream containers do not have that which may be termed a flange, but they do have a thin metal beading around the upper edge. While such beading does not offer much purchase for prior devices, it is an object of my invention to take advantage of such beading to assist the device, but my invention does not depend upon lifting or supporting a carton solely through such media.

As before mentioned, the invention does not limit itself to cartons of this class or to a specific thickness or strength of material, and it is another object of the invention to provide a device embodying and combining the advantages of several of the prior devices in such manner that the device acts selectively to employ to best advantage the action or actions best suited to the particular condition.

With respect to ice-cream containers, it is an object of the invention to provide a device for lifting and carrying same without removal of the cover thereof and even, when repeatedly acted upon by the device, the container will not develop a leak and thereby taint or damage the contents of the container.

Other objects and advantages of my invention will appear hereinafter and will be better understood by reason of the order in which they appear.

I have illustrated by the accompanying drawings some practical embodiments of my invention.

Figure 1 of the drawing shows in vertical section an embodiment suited particularly for lifting paper cartons of the class described, although it embodies the more salient feature of the invention and in corresponding proportions is likewise adapted to a variety of other uses.

Figure 2 of the drawing is a cross section thereof seen on the line 2—2 of Figure 1.

Figure 3 is a small scale view in side elevation of modification embodying means for lifting a single carton as well as means for simultaneously lifting a pair of cartons.

Figure 4 is a detail showing of the pad for engaging the outside of the container.

The device shown in Figure 1, in common with devices of the prior art, consists mainly of the handle or grip 5 extending inwardly from other parts of the device in a generally horizontal plane; this handle being bent at 6 substantially right-angular and continuing downwardly to terminate in spaced extensions 7 and 8 respectively; one extension being longer than the other.

The extension 7 is relatively short and is known 55

hereinafter as the abutment and is adapted to contact the inner surface 9 of the carton wall 10, or to similarly contact the corresponding surface of any other wall.

5 Extension 8, while paralleling extension 7, is spaced therefrom a distance considerably in excess of the thickness of a container wall to provide between itself and extension 7 the clearance space indicated at 11. An appreciable distance 10 below the lower termination of extension 7 the second named extension turns inwardly as at 12 and terminates in an arcuate contact pad 14.

This contact pad provides one of the salient features of the invention and is of increased 15 width with respect to the extension 8, of which it is substantially an integral part. The contour of this arcuate contact pad, in the particular embodiment being described, is such as to conform closely to the outer circumference of the 20 carton wall 10, and its circumferential extent with respect to the carton wall shall be such as to cause it to perform as hereinafter described.

It is a peculiarity of this contact pad that its 25 inner surface 15 centrally is practically in vertical alignment with the inner surface 16 of extension 7 so that when the abutment 7 is in co-extensive contact with the inner surface of the container wall the contact pad is in similar co-extensive contact with the outer surface of the 30 container wall. This relative disposition of surfaces, shown particularly in Figure 1, indicates that when the extensions are in vertical position with the device in operative or lifting position, the engaged wall of the container is also 35 truly vertical.

These respective positions of correlated parts take advantage of the center of gravity of a suspended container so that when the usual lifting force is applied to the handle 5 the container 40 takes on a normal vertical position which insures against ready dislodgment of the container during motions arising when a person is walking while carrying a container with this device. As is demonstrated by a person raising an open-top container vertically with the aid of the thumb and a finger, this device will, with no means other than friction of the surfaces 15 and 16 respectively, at corresponding surfaces of the container wall, act to suspend a container, but in 45 order to do so effectively it is essential that the point of frictional contact at the other surface of the carton be definitely located only at a point well below where the inner frictional contact takes place. Hence the purpose of off-setting extension 8 with respect to extension 7. This 50 offset not only confines frictional contact of the outer extension to the contact pad 14, but it also provides the clearance space 11 which is particularly essential where I employ the instrumentalities about to be described.

One of these consists of a one-way clutching and piercing element 18 carried at the inner surface of the contact pad and a short blunt pin 19 carried by and projecting slightly from the inner surface of abutment 7. Since these projections overlap each other when considered in the vertical plane, it is apparent that the device cannot be placed in operative position over the carton wall, or as readily removed, without there being 55 the clearance space 11 between them to permit of the device being properly inclined or cocked when being set over, or when being removed from, the carton wall.

The short blunt pin 19 need only be capable of 75 engaging the thin lower margin of the thin metal

rim or beading 20 found on ice-cream cartons and the like, and where the device is used for lifting other articles I find that the same short, blunt, small-diameter pin 19, is all that is needed to set up a very decided frictional hold on a corresponding surface without damage thereto.

The one-way clutching and piercing element 18 is here shown as being a larger diameter pin or the like which has been cut or machined at its protruding end to an inclined surface 21 thereat, extending downwardly-inwardly toward the inner surface of the contact pad. This surface characteristic of the pin provides that the pad may be moved downwardly over a surface, such as the outer surface of the carton wall, in slight frictional contact therewith without tearing or engaging same although when moved upwardly in frictional contact therewith it will tend to engage or bite into the material of which the wall is made. It is not intended that this sharp- 20 end pin shall act to perforate entirely through the container wall and as we shall learn hereinafter, the contact pad co-operates therewith in such manner that complete penetration of the wall by the sharp pin is neither essential or normally possible, nor does the device depend upon the carton being supported entirely by this sharp-end pin.

The various elements of the device have been described without mention of the actual material used in constructing the device and it is apparent to those skilled in the mechanical arts that a single forging, casting, or the like, will serve. It is, however, an object of the invention to adapt the device to mass production at low 30 cost while providing a decidedly rugged or long-lived instrument. It will be understood that those persons employing a device of this kind are prone to use it either thoughtlessly or deliberately as an all-purpose tool for chipping, hammering, prying, and the like. Also it is essential that the device be so constructed as to offer clean, smooth surfaces adapting it to initial plating and subsequent sterilizing required of all dairy equipment. In the embodiment 40 shown, so-called flat-convex strap iron stock is used and beginning with the extension 7, this stock continues to form the lower half of the handle 5, then turns over upon itself in an open loop 22, and then back to form the upper half 45 of the handle and continuing to form the extension 8. Although the pad 14 is described as being a substantially integral part of the extension 8, it is actually manufactured separately, for obvious reasons, and then secured in place as by 50 the rivets 17 on end 8a, or by spot welding if that be more desirable. The handle and its loop are arranged to insure a good grip; the loop being enlarged and so angled at the larger end of the loop as to afford a firm grip and thus to prevent the device slipping from the hand of a person carrying a carton thereby; it being understood that in use the handle is more apt to be moist than dry, and in particular, when the device is in use in handling ice cream cartons.

Using the device to first engage a paper carton, particularly one filled with ice cream and having the cover in place, the device is applied by passing the contact pad downwardly along the outer side of the upper part of the carton wall 70 until the sharpened end 7a of extension 7 comes in contact with the cover. This movement of the device downwardly with respect to the carton is continued forcibly so that the extension 7 breaks through the cover of the paper carton, if it be 75

so covered, and disposes the short blunt pin 19 just below the lower and inner edge of the beading 20. Meanwhile, the pin 18 on the contact pad has been passing freely over the corresponding outer surface of the carton. Now the device is lifted naturally so that the extensions take on a vertical position which causes the carton wall to become wedged between the ends of the pins 18 and 19 respectively. In some instances, the pin 18 will at once bite into the wall of the carton and prevent relative upward movement of the device with respect to the carton. In other instances it may slip slightly, allowing the device to be raised without the carton until the short blunt pin 19 shall have engaged the beading. Again the motion of the device, without forethought on the part of the user, may be such that the pins frictionally engage respective surfaces equally and simultaneously so as to lock the device to the carton wall. In any event, by one reaction or another, the act of raising the device vertically causes the offset weight of the carton to react through the abutment member to move the carton wall forcibly against the pin 18 carried by the contact pad. I have found a single central pin to be most effective since when the wall is forced against this pin it will, in the case of a paper carton, deform and depress in the vicinity of the pin and allow the contact pad to abut non-deformed areas surrounding the pin and thus prevent the pin from penetrating the paper unduly, if at all. As soon as the pad is in such position it holds the device and handle properly aligned with the carton so that the handle proper assumes a position truly diametric of the carton. At the same time the pad has a coefficient of friction now manifest to an extent to materially assist in carrying the load and relieving the pin 18.

To accurately account for the relative lifting and clamping effect of the pins and friction surfaces is indeed difficult and for any type of carton or other vertical wall to be engaged it is difficult to predetermine which of the several features will be most effective and which can be dispensed with, but I do know that in some instances one pin can be dispensed with, and in other cases both can be dispensed with, while in the case of paper ice-cream containers the trade demands all of the features herein shown. However, I may say, that with the proper clearance space at 11, and with the surfaces of the pad 14 and of the abutment 7, treated according to requirements to provide the required friction or "bite," the invention is applicable to many and varied acts ranging from the relatively light task of lifting filled paper cartons, to lifting, (with device of proper size) huge tanks, or the like, and for engaging any wall where forces angularly to the direction of lift.

The embodiment shown in Figure 3 embodies the salient features of the embodiment shown in Figures 1 and 2, and in the drawings corresponding parts are designated by the same reference numerals. In this embodiment a single piece 24 of flat bar stock is bent centrally at 25 to provide two handles, 26 and 27 respectively; one right angular to the other and by turning the device accordingly, either may be placed in vertical operative position. At the extreme end of extension 26 is riveted a single contact pad such as 14 while at the extreme end of extension 27 two such pads are riveted in opposed position. In proper relation to the contact pad on extension 26 is secured a strip 28 of metal formed to provide at

one end a corresponding abutment such as 7 and this strip continues contiguously of the corresponding surface of the bent member 24 toward another of the pads and is there formed to provide a corresponding abutment member. The 5 abutment member for co-operation with the third contact pad is at the end of another piece of metal 29 attached contiguously of that surface of member 24 which is opposed to the surface at which strip 28 is secured. This strip 29 continues 10 along such surface to the bend 25 where it curves in the opposite direction to form a finger purchase 30 to assist the operator in carrying the load when the opposed pair of contact pads are being used. Obviously this last described embodiment provides three sets of lifting and carrying instrumentalities, two of which can be used simultaneously for carrying a pair of cartons.

Now I have found that the combination of the arcuate pad 14, its inner friction surface 15 and 20 its peculiarly pointed pin 18, provides a gripping action which differs materially from that of two spaced conically pointed pins such as found in prior devices. It seems that this new type of single central pin in the center of a large contact pad does not make a form of penetration which gives rise to leaks or tearing and that actually before it penetrates appreciably it tends to make a conical depression shown at 31 in the drawings and allows the surface 15 of pad 14 to come into 30 frictional engagement or abutment with the carton surface surrounding the depression 31. This produces a peculiarly effective type of engagement which resists very appreciable loads with less destructive action on the surface of the carton at the point of contact, and it is to be remembered that with the surface 15 of the pad 14 vertically aligned with the inner surface of abutment 7 proper application of the device to a carton wall is only possible by providing the clearance space 11.

While in the foregoing I have been specific as to constructions, arrangements of parts, and applications of the invention, such are only by way of example and do not act to limit the invention 45 to specific constructions, arrangements and uses respectively; the invention being of a broader scope as shown by the appended claims.

Having described my invention, that which I claim as new and patentable is:

1. In a lifting device for engagement with a vertical wall, the combination of a pair of spaced approximately parallel vertical members of unequal length providing a clearance space between them having a width greater than the corresponding dimension of said wall and each presenting to said space a corresponding abutment surface disposed each in substantially the same vertical plane as the other, and pins, one for and carried by each member projecting normally thereof from the corresponding abutment surface, one of said pins being short and blunt and the other being longer and pointed.

2. In a lifting device for engagement with a vertical wall, the combination of a pair of spaced approximately parallel vertical members of unequal length providing a clearance space between them having a width greater than the corresponding dimension of said wall and each presenting to said space a corresponding abutment surface disposed each in substantially the same vertical plane as the other, and pins, one for and carried by each member projecting normally thereof from the corresponding abutment surface, one of said pins being short and blunt and the other being

longer and having a downwardly-inwardly inclined surface terminating in a penetrating non-conical point.

3. In a lifting device for engagement with a vertical wall, the combination of a pair of spaced, approximately parallel vertical members of unequal length providing a clearance space between them of a width greater than the corresponding dimension of such wall; the shorter member presenting to said space an abutment surface for co-extensive frictional contact with one surface of such wall; the longer member adapted to extend in spaced, non-contacting, parallel relationship to the other surface of such wall to a point well below the termination of the shorter member; said longer member there turning inwardly of said space and presenting a relatively large area contact surface adapted to frictionally contact corresponding parts of the outer surface of said wall simultaneously with frictional contact of the upper inner surface of said wall by said shorter member, and a blunt or flattened pin carried by the shorter member to engage any adjacent projection on said wall.
5. In a lifting device for engagement with a vertical wall, the combination of a pair of spaced, approximately parallel vertical members of unequal length providing a clearance space between them of a width greater than the corresponding dimension of such wall; the shorter member presenting to said space an abutment surface for co-extensive frictional contact with one surface of such wall; the longer member adapted to extend in spaced, non-contacting, parallel relationship to the other surface of such wall to a point well below the termination of the shorter member; said longer member there turning inwardly of said space and presenting a relatively large area contact surface adapted to frictionally contact corresponding parts of the outer surface of said wall simultaneously with frictional contact of the upper inner surface of said wall by said shorter member, and a pin carried by the longer member projecting normally from said contact surface, and cooperating therewith to frictionally engage said wall without complete penetration thereof.
4. In a lifting device for engagement with a vertical wall, the combination of a pair of spaced, approximately parallel vertical members of unequal length providing a clearance space between them of a width greater than the corresponding dimension of such wall; the shorter member presenting to said space an abutment surface for co-extensive frictional contact with one surface of such wall; the longer member adapted to extend in spaced, non-contacting, parallel relationship to the other surface of such wall to a point well below the termination of the shorter member; said

longer member there turning inwardly of said space and presenting a relatively large area contact surface adapted to frictionally contact corresponding parts of the outer surface of said wall simultaneously with frictional contact of the upper inner surface of said wall by said shorter member, and a blunt or flattened pin carried by the shorter member to engage any adjacent projection on said wall.

5. A device of the class described comprising a length of flat-surface bar stock beginning with a vertical abutment, thence rising vertically an added distance, then turning at approximately right angle thereto to form a lower handle extent, then bending over upon itself to form a large open loop, then continuing approximately parallel of the lower handle extent to form an upper approximately horizontal upper handle extent, then bending to continue vertically downwardly parallel to that portion rising vertically from said abutment, then bowed away from said abutment and continuing vertically downward in spaced parallel relationship to said abutment to provide a wide clearance space therebetween and continuing thus well below said abutment and there bowing inwardly again and providing thereat a relatively large area abutment surface in substantially the same vertical plane as the corresponding surface of the abutment member; and projecting pins in vertical alignment, one for and projecting normally from each abutment surface, that pin projecting from the large area abutment surface cooperating therewith to frictionally engage a deformable curved wall without complete penetration thereof.

CLAUDE W. DAVIS.
